J. W. ORROCK.
MILL TYPE DOOR.
APPLICATION FILED JAN. 24, 1920.

1,389,211.

Patented Aug. 30, 1921.

UNITED STATES PATENT OFFICE.

JOHN W. ORROCK, OF MONTREAL, QUEBEC, CANADA.

MILL-TYPE DOOR.

1,389,211.

Specification of Letters Patent. Patented Aug. 30, 1921.

Application filed January 24, 1920. Serial No. 353,664.

To all whom it may concern:

- Be it known that I, JOHN WILSON ORROCK, a subject of the King of Great Britain, and resident of the city of Montreal, in the Province of Quebec and Dominion of Canada, have invented certain new and useful Improvements in Mill-Type Doors; and I do hereby declare the following is a full, clear, and exact description thereof.
- 10 My invention relates to doors for engine houses, shops, freight sheds and other buildings and its object is to provide a composite door which will be substantially as strong and durable as a metal door.
- 15 To this end my invention consists of a metal frame with flared corners, around which is built a series of wooden strips with means for securing the parts together so that on completion there is evolved a mill type
- 20 wooden door flat on both sides with steel corners and vertical and horizontal steel supports to which the door fastenings can be applied for operating independently of the woodwork.
- 25 The primary advantages to this type of door are great lateral stiffness, an all steel support with a minimum amount of metal and smooth sliding surfaces on both sides for easy operation.
- 30 For full comprehension, however, of my invention, reference must be had to the accompanying drawings in which similar reference characters indicate the same parts, and wherein:

35 Figure 1 is a front elevation of a pair of doors constructed according to my invention;

Fig. 2 is a vertical sectional view taken on line 2—2 Fig. 1;

40 Fig. 3 is a horizontal sectional view taken on line 3—3 Fig. 1; and

Fig. 4 is a detail view illustrating the steel reinforcing frame.

My improved door is built up from a skeleton frame of metal. This skeleton frame consists of vertical side frame members 2 and 3 respectively and horizontal top and bottom members 5 and 6 respectively, the abutting ends of these members being bent 45 outwardly as at 4 relatively to the frame at an angle of 45° to the frame members, thus causing the abutting bent ends to coincide and form a radial corner extension, the ends of which form the corners of a 50 rectangular figure longer and wider than the frame proper. These frame members

preferably consist of angle irons and the contacting flanges 9 of the radial corner extensions are fastened together by rivets or bolts 10. The frame thus formed is braced 60 or stiffened by transverse members 7 and 8. The corners of this frame and the points of connection between the angle-irons 7 and 8 and 2 and 3 are strengthened by gusset plates 12. Upon this frame the wooden 65 structure is mounted. This wooden structure consists of vertical stiles 13 and 14, top and bottom rails 15 and 16, central rails 17 and panels 18 and 19. Where two doors are employed for closing the door opening it 70 may be necessary to provide one of them with a wicket 21 the construction of each however, being otherwise in all respects the same.

The stiles 13 and 14 are constructed of a 75 multiplicity of vertically disposed wooden strips the fastenings for securing one strip in place being covered up by the next adjacent strip, thereby protecting them from the weather and also from fumes which are 80 so prevalent in locomotive and other shops. The top, bottom and central rails 15, 16 and 17 respectively are also constructed of a multiplicity of strips horizontally disposed and secured together in the same manner, the 85 ends being cut off obliquely to fit between the oblique projections 4 at each corner of the metal frame and the stiles and rails are rigidly secured to the frame by bolts 21 extending at right angles to the length of the 90 strips composing each wooden member and having their heads respectively countersunk in the outside strips of each of the stiles and top and bottom rails and the outside strips 22 of the panels 18 and 19. These outside 95 strips extend parallel to the angle irons to which they are secured so that the strips 22 adjacent the top and bottom rails are disposed horizontally, the others adjacent the angle-irons 2 and 3 being disposed vertically. 100 The central rail is similarly constructed, interposed between the flanges 23 of the angle-irons 7 and 8 and a strip 24 on the opposite side of each of such flanges, the whole being secured together by bolts 25 with their heads 105 countersunk in the strips 24.

This construction presents a mill type wood and metal door for engine houses and the like in which the metal is a frame presenting openings in which the wooden panels 110 are set and by which these wooden panels are carried and reinforced. In order to

increase the durability and fire-resisting properties of my improved doors each of these panels is composed of a multiplicity of vertically-disposed wooden strips of similar dimensions to those in the parts hereinbefore referred to. These doors when completed may be mounted in the door opening in any preferred manner either by suspending them from their upper ends by pivots or 5 by hinging the steel frame independently of the wood. The hinging and pivoting of the door through its metal skeleton frame is facilitated by plates 120 fastened rigidly to the radial extensions at the hinged corners of the doors and extended over the top and bottom rails as shown in Figs. 1 and 2 and illustrated in detail in Fig. 4.

If desired the upper panel of each door may be constituted by a window-sash. The 20 frame of the sash would in this instance be constituted by the strips 22 and 24.

The metal frame *per se* is a feature of my invention and although it is particularly adapted to a filling of mill type, it may serve 25 as the support for other types of doors than mill type and may be employed by me with or without the gusset plates 12 and cover plates 120 indicated at the hinged corners of the double doors of Fig. 1 and in detail in 30 Fig. 4.

The doors illustrated in Fig. 1 of the drawing are adapted to be hinged upon trunnions which extend from the top and bottom edges thereof.

35 What I claim is as follows:

1. A mill-type door consisting of a metal frame and a multiplicity of wooden strips secured together, the fastenings for securing one strip in place being covered by the 40 next adjacent strip.

2. A mill-type door consisting of a metal frame with flared corners and a plurality of

wooden parts mounted upon said frame each of said parts comprising a multiplicity of wooden strips secured together. 45

3. A skeleton frame for a door consisting of vertical and horizontal frame members the abutting ends of which are bent outwardly to present radial extensions; and means rigidly fastening the extensions together. 50

4. A skeleton frame for a door consisting of vertical and horizontal metal frame members the abutting ends of which are bent outwardly to present radial extensions; and 55 means rigidly fastening the extensions together.

5. A skeleton frame for a door consisting of vertical and horizontal metal frame members the abutting ends of which are bent outwardly to present radial extensions; means 60 rigidly fastening the extensions together; and a plate fastened rigidly to the extensions and extending therefrom for the purpose set forth. 65

6. A mill-type door comprising a metal frame consisting of vertical and horizontal frame members the abutting ends of which are bent outwardly to present radial extensions; means rigidly fastening the extensions together, and plates fastened rigidly to the extensions and extending therefrom 70 for the purpose set forth, and a plurality of wooden parts mounted upon said frame 75 each of said parts consisting of a multiplicity of wooden strips secured together.

In testimony whereof I have signed my name to this specification in the presence of two witnesses.

JOHN W. ORROCK.

Witnesses:

T. RUTH,
F. M. DUCKETT.
